UNITED STATES PATENT OFFICE.

EDWARD J. KOCH, OF CHICAGO, ILLINOIS.

DESIGN FOR A GLASS DISH.

SPECIFICATION forming part of Design No. 35,918, dated May 20, 1902.

Application filed April 26, 1902. Serial No. 104,882. Term of patent 3½ years.

To all whom it may concern:

Be it known that I, EDWARD J. KOCH, of Chicago, in the county of Cook and State of Illinois, have invented a certain new and original Design for Glass Dishes; and I do hereby declare the following to be a full, clear, and exact description of the invention, such as will enable others skilled in the art to which it appertains to make and use the same.

10 The distinguishing characteristics of my design for glass dishes will be hereinafter clearly pointed out, reference being had to the accompanying drawings, wherein are views, as follows:

15 Figure 1 is a side view. Fig. 2 is a similar view showing the article on a quarter-turn. Fig. 3 is a bottom plan view.

20 The leading features of my design consist of a wreath almost entirely inclosing a hob-star, together with a miter-like representation between the branches of adjacent wreaths, the lower ends of the wreaths being inclosed by lines which surround a central figure.

25 Referring to the drawings, 1 designates the wreaths; 2, the stars partly inclosed thereby;

3, the miter-like representations, and 4 the figure at the center of the bottom of the dish, which is surrounded by irregular intaglio lines or grooves 5. These latter intersect one another at 6, presenting a pointed star-like 30 form at the inner end of the ornamentation 7 at the bottom of the miter-like representation 3. The edges of the lines or grooves 5 surrounding the lower or inner end of each wreath are curved inward toward the meeting ends of the 35 two branches of each wreath. All the decorations referred to are produced by cutting or forming surface grooves in the manner characteristic of cut glassware.

I claim as my invention—

40 The design for a glass dish, substantially as herein shown and described.

In testimony whereof I have signed this specification in the presence of two subscribing witnesses.

EDWARD J. KOCH.
